Primary Examiner — Jennifer L Watkins*Assistant Examiner* — Samantha Lynne Brodowski(74) *Attorney, Agent, or Firm* — Daniel N. Smith(57) **CLAIM**

The ornamental design for a reusable bag with a re-writeable surface, as shown and described.

DESCRIPTION

FIG. 1 is an isometric view of a reusable bag with a re-writeable surface showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.
